UNITED STATES PATENT OFFICE.

ROBERT L. MEYERS, OF SAN FRANCISCO, CALIFORNIA.

FRUIT-JUICE EXTRACTOR.

1,228,342.

Specification of Letters Patent.

Patented May 29, 1917.

Application filed May 8, 1916. Serial No. 96,040.

To all whom it may concern:

Be it known that I, ROBERT L. MEYERS, a citizen of the United States, residing in the city and county of San Francisco and 5 State of California, have invented new and useful Improvements in Fruit-Juice Extractors, of which the following is a specification.

This invention relates to fruit juice extractors and has for its object to extract the juices and reduce the pulp of fruit in an improved and efficient manner.

In carrying out this object I employ a simple and inexpensive device comprising a rotary bit of improved form, detachably carried upon a spindle journaled vertically in a frame, driving means for the spindle, a bucket carried removably upon the frame in an upright position surrounding the bit and 20 a clamping device for attaching the frame to a stationary object.

One form which my invention may assume is exemplified in the following description, 25 illustrated in the accompanying drawing in which—

Figure 1 shows a side elevation partly in section of a device embodying my invention, and

Fig. 2 shows a plan view of the same with 30 certain of the parts broken away for the sake of clearness.

Referring in detail to the form of my invention illustrated herewith, a frame 10 is shown upon which is journaled a vertical 35 spindle 11. The upper end 12 of the spindle is made angular in cross section to detachably receive a bulbed bit 13, the latter being provided with longitudinal ribs 14 and adapted to operate upon the pulp of a 40 severed portion of the fruit.

Detachably held on the frame by means of a nut 15 screwed to the bearing 16 is a bucket 17 surrounding the bit and adapted to catch the juice and pulp extracted from the fruit, 45 said bucket having a spout 18 near its bottom to discharge the juice.

Bearing 16 is cored and at the inner end of the squared extremity 12 of spindle 11, an annular part is formed which is received 50 in the hollow bearing 16 to support the spindle in an upright position.

For driving the spindle either, or both, hand and power means may be employed. A power means is shown as comprising a

pulley wheel 19 on the spindle to receive a 55 belt 20, and the hand means comprises a bevel pinion 21 on the spindle meshing with a bevel gear 22, the latter journaled on a stud 23 fixed to the frame and having a crank handle 24 for imparting motion thereto. 60

The frame is provided with jaws 25 to fit over the edge of a table or bench or other support 26 and the lower jaw has a clamp 27 carried on a thumb screw 28 for securing the frame in place. 65

In the operation of the device described, fruit such as oranges, lemons, limes, etc., is first cut in halves and each half held with its severed portion upon the rotating bit and pressed thereon by the operator. The action of the bit is to grind the pulp and reduce the same so that the juice is entirely removed. Such an extractor offers advantages over the squeezers heretofore in use in that it does not force any of the acids 75 from the peel and does not leave any of the fruit juice in the pulp. The bits are easily removed and replaced and in practice several sizes and shapes may be provided for this purpose. The bucket is easily removed 80 for cleaning and its arrangement is such that all juice is certain to be caught. In changing from hand operated to power operated driving means, the beveled gear 22 may be removed or disengaged from the pinion by 85 withdrawing the stud 23, which is held in place by means of a set screw 29.

While I have shown and described but one form of my invention herein, it will be understood that the same is susceptible of 90 modification and that changes in the construction and arrangement of the several parts may be employed without departing from the spirit of the invention as disclosed in the appended claim. 95

Having thus described my invention, what I claim and desire to secure by Letters Patent is—

In a fruit juice extractor, a supporting frame, a bucket having a central opening, 100 one end of the frame extending upwardly and passed through said opening and being cored to provide a vertical hollow bearing, an operating spindle extending through the bearing and having a squared extremity and 105 having an annular part at the inner end of said squared extremity, said annular part of the squared extremity being positioned with-

in said hollow bearing of the frame to support the spindle in an upright position, a bulb bit having a squared opening embracing the squared end of the spindle, and 5 means engaging over the upwardly extending end of the frame to clamp the bucket thereagainst.

In testimony whereof I have hereunto set my hand in the presence of two subscribing witnesses.

ROBERT L. MEYERS.
